CLAIM

The ornamental design for an accessory shoe for a camera, as shown and described.

DESCRIPTION

FIG. 1 is a right rear perspective view of an accessory shoe for a camera showing my new design;

FIG. 2 is a top plan view thereof;

FIG. 3 is a rear elevational view thereof;

FIG. 4 is an enlarged plan view thereof;

FIG. 5 is an enlarged rear elevational view thereof; and
FIG. 6 is an enlarged right side elevational view
thereof.

The broken line portions of the drawing are for illustrative purposes only and form no part of the claimed design.

FIG. 1

FIG. 2

FIG. 3

FIG. 4

FIG. 5

FIG. 6
